UNITED STATES PATENT OFFICE.

WILHELM WECKERLE, OF STUTTGART, GERMANY.

MEANS FOR RETURNING CONDENSATION-WATER TO THE GENERATOR.

No. 841,748.

Specification of Letters Patent.

Patented Jan. 22, 1907.

Application filed October 15, 1906. Serial No. 338,990.

To all whom it may concern:

Be it known that I, WILHELM WECKERLE, a subject of the German Emperor, residing at Stuttgart, Württemberg, Germany, have invented an Improved Method and Means for Returning Condensation-Water from Steam-Cookers and the Like to the Steam-Generator, of which the following is a specification.

This invention relates to an improved method of and an automatic reversing-valve for returning the condensation-water from steam-cookers to the steam-generator, the object being to utilize the difference of steam pressures in the generator and the cooker to operate said reversing-valve through the intervention of an internal float adapted to be lifted by the condensation-water. This is effected by causing the live steam after it has performed its work in the reversing-valve to join the steam in the cooker.

Steam-cookers have heretofore been provided with means for returning the condensation-water to the steam-generator, and my invention comprises only the aforesaid reversing-valve and the manner of operating the same.

The invention will be readily understood by reference to the accompanying drawings, in which—

30 Figure 1 is an elevation, partly in section, of the general arrangement of my improved steam-cooker. Fig. 2 is a vertical section of the reversing-valve.

Between the cooker *a* and steam-generator *b* I place the reversing-valve, which consists of two cylinders *c* and *s*. The lower and larger cylinder *c* receives the condensation-water and is provided with a piston *d* and a float *f*, adapted to slide on a central vertical rod *e*. The rod *e* projects with its upper end in the hollow piston-rod *g* and has a longitudinal slot *h*, in which a pin *i* of the float *f* can slide up and down.

The lower end of the rod *e* is pivoted to a two-armed lever *k*, whose external arm *l* is pivotally joined to a piston *m* by the piston-rod *n*. The piston *m* can slide in its steam-box *o*, which receives live steam from the generator *b* through a branch pipe *p*. The steam-box *o* has a port *q*, which leads to the back of the piston *d*, and a port *r*, leading

to the rear of the piston *t*, fixed to the upper end of the piston-rod *g* and sliding in the small cylinder *s*. A further port *u* leads from the box *o* to the front of the piston *t*. Moreover, the said box has ports *v* communicating with its upper and lower end, leading by a pipe *w* into the steam-space of the cooker *a*. The main steam-pipe *x* from the generator *b* supplies the piston-valve *m* through the branch pipe *p*, as stated, and also passes through a pressure-reducing valve *y* direct into the steam-space of the cooker.

The action is as follows: The generator *b* may have a normal steam-pressure of eight atmospheres, which pressure would be reduced by the valve *y* to two atmospheres before the steam can enter the steam-space of the cooker *a*. The condensation-water passes away through the pipe *z* into the lower end of the cylinder *c*, where it forces the float *f* upward, the pin *i* therefore sliding along the slot *h* of the rod *e*. When the pin *i* reaches the upper end of the slot *h*, it lifts the rod *e*, which latter operates the two-armed lever *75* and causes the rod *n* to move the piston *m* into the lower position, as shown at Fig. 2. Steam now enters from the pipe *p* through the port *r* to the rear of the piston *t*, as well as through the port *q* behind the piston *d*, and causes both pistons to descend, with the result that the condensation-water is ejected from the cylinder *c* through a forwardly-situated non-return valve into the generator, its passage with the cooker being barred by a rearwardly non-return valve. Shortly before the completion of the stroke of the two pistons *d* and *t* the latter strikes the upper extremity of the rod *e* and depresses the same, thus causing the piston-valve *m* to be *90* reversed and allow steam to enter the port *u* and lift the piston *t* and its connected piston *d*. The float *f* remains at the bottom of the chamber *c* until it is again forced upward by fresh condensation.

95

I claim—

In steam-cookers, the arrangement of an automatic reversing-valve between the cooker and the steam-generator and comprising in combination a large cylinder, a piston, an outwardly-projecting piston-rod, a small piston at the end a float in the large cylinder, an

internal rod operated by said float in one direction and by said small piston in the opposite direction, a two-armed lever pivoted to said rod, an external rod pivoted to the lever,
5 a piston-valve mounted on said external rod and a valve-box containing said piston-valve with ports therefrom into the two cylinders,

and ports for alternately bringing said cylinders in communication with the steam-space of the cooker.

WILHELM WECKERLE.
